UNITED STATES PATENT OFFICE

ERWIN J. PAULI, OF BROOKLYN, NEW YORK, ASSIGNOR TO DOEHLER FURNITURE CO.
INC., A CORPORATION OF NEW YORK

DESIGN FOR A NIGHT TABLE OR THE LIKE

Application filed April 16, 1930. Serial No. 35,271. Term of patent 7 years.

To all whom it may concern:

Be it known that I, ERWIN J. PAULI, a citizen of the United States, and a resident of Brooklyn, in the county of Kings and State of New York, have invented and produced a certain new, original, and ornamental Design for a Night Table or the like, of which the following is a specification, reference being had to the accompanying drawing, forming part thereof, wherein the figure is a perspective view of a night table showing my new design.

I claim:

The ornamental design for a night table or the like, as shown.

ERWIN J. PAULI.
